J. B. OLDS.
SEMITRAILER ELEVATING HORSE.
APPLICATION FILED OCT. 17, 1918.

Patented July 8, 1919.

Inventor
James B. Olds

UNITED STATES PATENT OFFICE.

JAMES BRYANT OLDS, OF MASPETH, NEW YORK.

SEMITRAILER ELEVATING-HORSE.

1,308,764.

Specification of Letters Patent.

Patented July 8, 1919.

Application filed October 17, 1918. Serial No. 258,507.

To all whom it may concern:
Be it known that I, JAMES BRYANT OLDS, a citizen of the United States, and residing at Maspeth, L. I., in the county of Queens and State of New York, have invented certain new and useful Improvements in Semi-trailer Elevating-Horses, of which the following is a specification, such as will enable those skilled in the art to which it appertains to make and use the same.

This invention relates to the coupling of what are known as semi-trailers with a motor or tractor and uncoupling the same when desired; and the object of the invention is to provide improved means or apparatus of the class specified whereby the operation or operations referred to may be quickly and easily accomplished without danger to the operator or operators; a further object being to provide an apparatus of the class specified which is simple in construction and operation and comparatively inexpensive; and with these and other objects in view the invention consists of the apparatus hereinabove described and claimed.

The invention is fully disclosed in the following specification, of which the accompanying drawing forms a part, in which the separate parts of my improvement are designated by suitable reference characters in each of the views, and in which:—

Figure 1 is a side view of my improvement and indicating the method of its use;

Fig. 2 a side view of a horse jack device which I employ;

Fig. 3 a front view thereof;

Fig. 4 a plan view of a runway device which I employ; and,

Fig. 5 a cross section on the line 5—5 of Fig. 4.

In the accompanying drawing I have indicated at *a* an ordinary motor or tractor and at *b* what is known as a semi-trailer comprising a body portion *b*² and rear axle *b*³, having wheels *b*⁴, and the chassis of the motor or tractor is provided in the usual way with a backwardly directed extension *a*² and, in the practice of my invention, I provide a horse jack device *c* and an inclined runway *d* which are indicated in use in Fig. 1, and shown separately and in detail in Figs. 2 to 5 inclusive.

The general form of the runway *d* is well known, and said runway may be of any preferred construction, but in the accompanying drawing consists of parallel side

members *d*² connected by transverse rods, bars or other devices *d*³, and at the bottom of the front and deeper end portion thereof is a shaft *d*⁴ provided with wheels or rollers *d*⁵, and by taking hold of the rear end parts *d*⁶ of the side members *d*², the runway device *d* may be manipulated or wheeled about from one point to another in the manner of an ordinary wheel-barrow. 65

The horse jack device *c* comprises an upright framework *c*², the sides of which are preferably inclined inwardly and upwardly, and on the top thereof is placed a plate *c*⁴ which is preferably downwardly and forwardly inclined, and at the bottom thereof the horse jack device *c* is provided with front wheels *c*⁵ and rear wheels *c*⁶ which are adapted to travel on the sides *d*² of the runway *d*, and to facilitate this operation the 75 wheels *c*⁵ and *c*⁶ are provided, in the construction, with grooves *c*⁷ and the sides *d*² of the runway *d* with longitudinal ribs *d*⁷ which fit in said grooves.

The operation will be readily understood 80 from the foregoing description when taken in connection with the accompanying drawing and the following statement thereof. In Fig. 1 of the accompanying drawing the front end of the trailer is shown coupled to the motor or tractor at *e* in the usual manner, and whenever it is desired to disconnect the trailer from the motor or tractor, the runway device *d* is placed under the central portion of the trailer and in front of 85 the rear wheels *b*⁵ thereof, and the horse jack *c* is placed in front of the runway device with the wheels *c*⁵ resting on the rear end portions of the sides *d*² of the runway device *d*, and said runway device and said 90 horse jack device are so positioned under the trailer that the front part of the horse jack will be in contact with the rear end of the backwardly directed extension *a*² of the chassis of the tractor. 100

With the parts in this position the tractor is moved backwardly, which operation also moves the trailer backwardly, and in this operation the horse jack *c* is forced backwardly into the position shown in dotted 105 lines in Fig. 1, which operation raises the trailer or the free end portion thereof and disconnects it from the tractor as is also clearly indicated in Fig. 1, and after this operation the wheels *b*⁴ of the trailer are 110 blocked as shown at *f*, and the tractor moved forwardly from beneath the trailer and the

trailer remains supported in the position indicated in dotted lines in Fig. 1, and in this operation the horse jack may also be blocked on the runway *d* as shown at *g*. In order 5 to re-couple the trailer with the tractor, all that is necessary is to back the tractor under the trailer as indicated in Fig. 1 so that the end portion *a*² of the chassis will strike the horse jack *c*, after which the blocks *f* 10 and *g* are removed and the tractor is moved forward slowly, and in this operation the horse jack *c* moves forwardly and downwardly over the runway *d* and the trailer is recoupled with the tractor as will be readily 15 understood, after which the horse jack and runway are removed.

In the operation of coupling and uncoupling trailers and tractors of the class herein referred to, it has been necessary to employ 20 ordinary hoisting jacks which were placed beneath and operated from beneath the trailer, and this has been a very dangerous operation and many serious and fatal accidents have resulted therefrom, but with 25 my improvement all such dangers are obviated and the operation of coupling and uncoupling the tractor and the trailer has been simplified and rendered much more expeditious than was heretofore possible, and many 30 other advantages will indicate themselves to those accustomed to the operation of the form of apparatus to which my improvement relates.

My invention is not limited in any way to 35 the details of the construction of the runway device *d*, nor to the details of the construction of the horse jack *c*, as herein shown and described, and many changes in and modifications of this construction may be 40 made, within the scope of the appended claims, without departing from the spirit of my invention or sacrificing its advantages.

Having fully described my invention what I claim as new and desire to secure by 45 Letters Patent, is:—

1. The herein described means for elevating or raising semi-trailers in the operation of coupling said trailers with and uncoupling the same from a tractor, comprising 50 an inclined runway having side track members, and a horse jack adapted to be placed beneath the trailer and to be operated as described, said horse jack being provided with wheels which operate in connection with the 55 side track members of the runway device.

2. In an apparatus of the class described for supporting semi-trailers in the operation of coupling and uncoupling the same with a tractor, an inclined runway adapted 60 to be placed centrally of and beneath the trailer rearwardly of the tractor, and a horse jack device placed beneath the trailer forwardly of the runway and in engagement with the rear end of the tractor, whereby 65 the backward movement of the tractor and

trailer will move said jack device upwardly onto said runway which operation will uncouple the trailer from the tractor.

3. In an apparatus of the class described for supporting semi-trailers in the operation 70 of coupling and uncoupling the same with a tractor, an inclined runway adapted to be placed centrally of and beneath the trailer rearwardly of the tractor and a horse jack device placed beneath the trailer forwardly 75 of the runway and in engagement with the rear end of the tractor, said jack device comprising an upwardly tapered or conically formed frame having an inclined top cross head, and roller devices secured to the bottom corner portions of the frame, said jack device being adapted to be moved upwardly onto said runway by the tractor in the backward movement thereof to uncouple the trailer from said tractor. 80

4. In an apparatus of the class described for supporting semi-trailers in the operation of coupling and uncoupling the same with a tractor, an inclined runway adapted to be placed centrally of and beneath the trailer 90 rearwardly of the tractor, and a horse jack device placed beneath the trailer forwardly of the runway and in engagement with the rear end of the tractor and with the top of the jack device in engagement with the bottom of the trailer whereby the backward movement of the tractor and trailer will move said jack device upwardly on said runway which operation will uncouple the trailer from the tractor. 95

5. In an apparatus of the class described for supporting semi-trailers in the operation of coupling and uncoupling the same with a tractor, an inclined runway adapted to be placed centrally of and beneath the trailer 100 rearwardly of the tractor, and a horse jack device placed beneath the trailer forwardly of the runway and in engagement with the rear end of the tractor and with the top of the jack device in engagement with the bottom of the trailer whereby the backward movement of the tractor and trailer will move said jack device upwardly on said runway which operation will uncouple the trailer from the tractor, and means for preventing the downward movement of said jack device on said runway. 110

6. In an apparatus of the class described for supporting semi-trailers in the operation of coupling and uncoupling the same with a 115 tractor, an inclined runway adapted to be placed beneath the trailer and composed of side track members connected by cross rods and a horse jack device placed beneath the trailer forwardly of the runway and in engagement with the rear end of the tractor, said jack device comprising a substantial framework having an inclined top, flaring sides and grooved wheels in the bottom corner portions thereof, said wheels being 120

adapted to operate in connection with the track members of the runway, substantially as shown and described.

7. In an apparatus of the class described for supporting semi-trailers in the operation of coupling and uncoupling the same with a tractor, a portable runway device comprising side and tapered track members connected by cross members, said runway being adapted to be placed beneath the trailer and a horse jack device placed beneath the trailer forwardly of the runway and in engagement with the rear end of the tractor, said jack device comprising a frame having flaring sides connected at the

top by an inclined cross head, and wheels mounted in the bottom corner portions of the frame, said wheels being adapted to operate in connection with the track members of the runway in the backward movement of the tractor and trailer to uncouple the trailer from said tractor. 20

In testimony that I claim the foregoing as my invention I have signed my name in presence of the subscribing witnesses this 25 14th day of October 1918.

JAMES BRYANT OLDS.
